(57) CLAIM

The ornamental design for a fabric wrap for head-mounted display, as shown and described.

DESCRIPTION

FIG. 1 is a front and right perspective view of a fabric wrap for head-mounted display;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a front and right perspective view thereof showing the fabric wrap in use on a head-mounted display.

The broken lines in the drawings are included for the purpose of illustrating environmental structure and form no part of the claimed design.
